No. 768,062.

PATENTED AUG. 23, 1904.

H. W. MATHER.

NUTCRACKER.

APPLICATION FILED MAR. 10, 1903.

NO MODEL.

UNITED STATES PATENT OFFICE.

HENRY W. MATHER, OF ROSEVILLE, NEW JERSEY.

NUTCRACKER.

SPECIFICATION forming part of Letters Patent No. 768,062, dated August 23, 1904.

Application filed March 10, 1903. Serial No. 147,079. (No model.)

To all whom it may concern:

Be it known that I, HENRY W. MATHER, a citizen of the United States, residing at Roseville, in the county of Essex and State of New Jersey, have invented certain new and useful Improvements in Nutcrackers, of which the following is a specification.

This invention relates to lever devices for cracking nuts, and particularly to hand-operated implements or devices for the purpose.

The object of the invention is in part to enable great power to be applied, so that a child may easily crack the hardest nut, and in part to provide against crushing the kernel of the nut by a limitation of the travel of the movable jaw. The construction is simple and produces an inexpensive implement.

In the drawings, which illustrate an embodiment of the invention, Figures 1 and 2 are similar side elevations of the device, the first showing the jaws open and the latter showing them closed or nearly closed. Fig. 3 is cross-section of the two jaws at their toothed portions, (at the point indicated by line α^3 in Fig. 1,) showing the concavity or flute in the face of the jaw. Figs. 4 and 5 are sectional detail views, on a larger scale, showing the spring at the joint. Fig. 6 is a section at α^6 in Fig. 1, showing the mounting of the cam-lever and cam.

1 is the fixed jaw of the nutcracker, and 2 is the movable jaw. These are hinged together at α and are provided with a spring 3 at the joint or hinge, which tends to throw the jaws open. The jaws turn about a screw or rivet 4, and the spring occupies a recess 5 in the boss on the fixed jaw. The fixed jaw 1 has an L shape—that is, it has a branch 1^a, which is substantially at right angles to its main portion, and this branch is recessed or slotted at 6 to receive and form a keeper for the free end of the jaw 2, as clearly shown in Fig. 2, where the branch 1^a is broken away to show the construction.

45 In the forked or slotted end of the branch 1^a is fulcrumed an operating-lever 7, which

carries a cam 8 and turns about a screw or fulcrum stud 9. It will be seen by reference to Fig. 6 that the cam 8 forms an integral part of the lever 7, but is reduced in the thickness.

The nut to be cracked is placed between the jaws, as indicated by the dotted lines at n in Fig. 1, and the lever 7 brought down, as indicated in Fig. 2, and the effect is to cause the cam 8 by bearing on the jaw 2 to close the jaws and crack the shell of the nut; but the play of the jaw 2 is limited, and by properly placing the nut only the shell will be cracked, the kernel being left substantially uninjured.

6c The jaw 1 has been referred to as fixed; but this is only for convenience of description, as the jaws both move relatively to each other.

The jaws will be toothed where they grasp the nut, as seen at 10, and will also be concave or fluted longitudinally at the point where the teeth are located, as seen in Fig. 3.

Obviously the screws 4 and 9 might be rivets. They are merely referred to as "screws," as these are employed conveniently for the purpose.

Having thus described my invention, I claim—

A nutcracker consisting of the following instrumentalities, namely, a toothed and longitudinally-fluted jaw 1, having an upright branch 1^a provided with a recessed keeper 6, a toothed and longitudinally-fluted jaw 2, hinged to the jaw 1 at α , a coil-spring 3 about the hinge-axis of the jaws and connected thereto at its respective ends, a lever 7 fulcrumed in the end of the branch 1^a above the recess 6, and a cam 8 carried by said lever and adapted to bear on the jaw 2 at its end.

75 80 85 In witness whereof I have hereunto signed my name, this 28th day of February, 1903, in the presence of two subscribing witnesses.

HENRY W. MATHER.

Witnesses:

PETER A. ROSS,
WILLIAM J. FIRTH.
